COLLAR FASTENING DEVICE

Carlos C. Goetz, New York, N. Y.

Application August 12, 1948, Serial No. 43,931

1 Claim. (Cl. 2—139)

1

This invention relates generally to devices that are used for fastening collars to the neck-bands of shirts.

The main object of the invention is to provide a collar fastening device of simple construction, which is permanently secured to the neck-band of the shirt and which serves to both close said neck band and to comfortably fasten a removable collar thereto.

A further object of the invention is to provide a collar fastening device of the character above described which will hold the collar in snug engagement with the neck-band of the shirt. To effectuate this object, the device includes a flexible shank secured to the neck-band of the shirt and is equipped with means at the end thereof for securing the other free end of the neck-band and the free ends of the removable collar without causing any inconvenience or irritation to the wearer and without putting the wearer to the trouble of inserting a finger inside of the neck-band of the shirt during the operation of fastening the collar to the neck-band.

A further object of the invention is to provide a collar fastening device to take the place of the usual "front" collar-button now generally used for securing the free ends of the neck-band and attaching the ends of the collar thereto, the said fastening device being inconspicuous, permanently attached to the neck band, free of projections which contact the neck of the wearer, and which does not detract from the appearance of the shirt and collar.

These objects and other incidental ends and advantages of the invention will hereinafter appear in the progress of the disclosure and as pointed out in the appended claim.

Accompanying this specification is a drawing showing a preferred form of the invention wherein:

Figure 1 is a view in perspective of a man's shirt equipped with the improved collar fastening device secured to one end of the neck-band.

Figure 2 is an enlarged sectional view of a portion of the shirt shown in Figure 1 through the plane 2—2 thereof.

Figure 3 is a view in perspective of the shirt of Figure 1 showing a collar attached at one end to the collar fastening device, the other end of the collar being free for completing the attachment to the said device.

Figure 4 is a perspective view of the shirt shown in Figure 1 showing a collar fully attached thereto by means of the collar fastening device.

Figure 5 is an enlarged sectional view of Figure 4 across the plane 5—5 thereof.

In accordance with the invention and the preferred form shown, numeral 10 indicates a man's shirt provided with a neck-band 11. 12 represents any type of collar adapted to be secured to

the neck-band and may have a rear button hole for securing the collar to the rear of the neck-band by the usual "back" collar-button, the said button hole and "back" collar-button not being shown in the drawing.

The improved collar fastening device is adapted to be used for securing the ends of the collar 12 to the neck-band 11 and is intended to serve as the usual "front" collar-button now generally used for securing the free ends of the neck-band 11 and attaching the collar ends thereto. Moreover, the device is permanently affixed to neck-band 11 and is not provided with any part which projects through the rear of the neck-band as is the case with the ordinary collar-button. Further, the device is flexible and under no circumstances can the same be forced against the neck of the wearer to cause possible injury or pressure.

The collar fastening device consists of a flexible shank 13 which is secured at the inner end 20 as by stitching 14 adjacent the free end 15 of the neck-band 11. The opposite end of flexible shank 13 is provided with a head member 16 which is of greater diameter than shank 13 and which is secured thereto in any conventional manner as by stitching through a depending stud 17. The stitching between stud 17 and the outer end of flexible shank 13 is indicated by numeral 18, said stitching penetrating an opening 19 in the stud. Of course, it is understood that head 16 may be secured in any other manner to shank 13 and may be of any suitable material such as a button of pearl, plastic, or metallic or non-metallic material. Shank 13 is elongated so that there will be sufficient room between the head 16 and the neck-band 11 secured through button hole 20 to accommodate the end thicknesses 21 and 22 of the collar-band of collar 12.

In Figure 3 the neck band 11 is shown closed by means of the collar fastening device and also shows the collar band end 22 engaged by the collar fastening device through the button hole 23. In Figure 4 collar band end 21 is shown also secured in place by means of the collar fastening device through button hole 24.

In appearance the collar fastening device hereabove described is no different from the conventional "front" collar-button after a detachable collar is secured thereon. Further, the device appears no different from a collar button as applied to the neck-band 11.

Flexible shank 13 of the collar fastening device is preferably constructed of fabric in a rod-like formation, or may consist of any type and shape of flexible core suitably covered or wound externally with thread. The flexibility of shank 13 makes the collar device durable especially from the standpoint of laundering. As is known, laundering has a deleterious effect on buttons sewn to a shirt such as button 25 on shirt 10.

Such buttons crack and become loose from the attaching thread 26 by virtue of starching and ironing in the laundering process. This may be attributed to the lack of flexibility or yield of the button securing means to the shirt. In the invention herein laundering has no effect whatsoever on the durability of the fastening device because of the length and flexibility of shank 13. Moreover, since the collar fastening device may be made of non-metallic material throughout, laundering will not cause any corrosion whatsoever.

Since shank 13 is secured to the collar-band 11 at its rear end as has been heretofore described by means of any type of stitching thread 14, such stitching will not be effected by the steps of the laundering process and is as permanently secured to the shirt as are the shirt seams. The head member 16 on the other hand is durable with respect to the steps of laundering and otherwise because of its spacing relative to the ends 15 of the neck-band and the ends of collar 12.

A feature of the device is that it binds the free ends of the neck-band and of the collar together so that the collar feels snug and is not likely to pull away from the neck-band. Moreover the device does not detract from the appearance of the shirt and collar but presents a normal appearance. Indeed, head 16 of the collar fastening device may have any desirable color either to match the shirt 10 or the attaching collar 12. I wish it understood that minor

changes and variations in location, integration, material and number of parts of the device may all be resorted to without departing from the spirit of the invention and the scope of the appended claim.

It is further understood that although a man's shirt has been illustrated, the invention is applicable to other garments of all types for men, women and children, and that the use of the term "man's shirt" in the specification and claim is not to be construed as exclusive.

I claim:

In the combination of a man's shirt having a neck band provided with a button hole adjacent one free end and a detachable collar having attaching button-holes, a button member, an elongated flexible shank connecting said button member to the neck band adjacent the other free end thereof whereby said button member is yieldably engageable with said neck band button-hole and said collar button holes together and selectively for rendering said neck band and collar adjustable to variations in the sizes thereof.

CARLOS C. GOETZ.
